EXPANSION END CLOSURE OR CAP FOR
TUBESJohn F. Levan, Elkhart, Ind., assignor to Excel
Curtain Company, Inc., Elkhart, Ind., a corpora-
tion of Indiana

Application November 29, 1938, Serial No. 242,974

3 Claims. (Cl. 220—24.5)

This invention relates to end closures or caps for tubes, which are readily applied to the tubes to permanently close the ends thereof and also which are particularly economical in construction and consist of few easily assembled parts. More specifically, it has for its object an end closure which consists of a head or cap and an annular series of prongs secured to the cap centrally thereof by a hollow rivet and a disk expander 10 coating with outwardly inclined end portions of the prongs to split them so that their end edges or the corners thereof bite into the inner surface of the tube, and a screw extending centrally through the cap and threading into the disk expander. The class of tube to which this cap is applied is formed up from a flat metal strip and used primarily for hand rails, hand holds, and the like, in buses and other vehicles, and also for framing of articles of furniture as seats, chairs, etc.

The invention consists in the novel features and in the combinations and constructions hereinafter set forth and claimed.

In describing this invention, reference is had to the accompanying drawing, in which like characters designate corresponding parts in all the views.

Figure 1 is an enlarged longitudinal sectional view of this end closure, the contiguous end portion of a tube being also shown.

Figure 2 is an expanded view of parts of the expansion end closure.

1 designates the cap or head, this being here shown as having a convex body portion 2 and a rim 3 which fits over the end of the tube T. The cap is formed with a central perforation or opening 4 and with an inwardly extending annular lip 5 forming a continuation of the opening, which 40 lip constitutes a hollow rivet.

6 designates an annular series of spring prongs having outwardly inclined ends 7, the edges of which bite into the inner face of the tube T. These prongs have a base portion 8 common to 45 a plurality or all of them, which base portion is formed with a central opening 9 for receiving the hollow rivet 5. After being mounted on the hollow rivet, the rivet is upset or spun over, and hence the prongs secured to the head 1. The 50 base portion 8 lies flatwise on the inner face of the base or the convex portion 2 thereof.

10 designates the expander which is in the form of a disk, this coating at its margin with the outwardly inclined ends 7 of the prongs 6, and being preferably formed with its margin bev-

eled at 11 for coating with the inclined surfaces on the end portions 7 of the prongs 6.

12 is the screw extending through the opening 4 in the hollow rivet 5 and threading axially into the disk 10, the screw having its head countersunk or located in the opening 4, which is larger than the interior of the hollow rivet, so that the head of the screw is practically flush with the outer face of the head 1 or the convex portion 2 thereof.

The rim 3 fits over the end margin of the tube and thus protects the edge of the tube which would otherwise be exposed against corrosion. These tubes are made up of layers with an intermediate layer of carbon steel and an outer layer of stainless steel. The rim of the cap protects the carbon steel against corrosion, and hence bleeding around the edge of the cap. The prongs are thus a unit capable of gripping tubes of various diameters, within limits, and capable of being attached to heads of various sizes to slip on the ends of the tubes of different sizes.

The prongs, owing to their construction, may be applied to caps for tubes of various diameters, as prongs of a given size are adapted to tubes of various inside diameters, and snugly grip tubes of different diameters by drawing in the expander disk 10 by means of the screw 12 more or less in accordance with the interior diameter of the tube T. In all cases, the cap is firmly held in position, due to the ends of the prongs biting into the tube, and hence the cap can not be removed by tamperers.

What I claim is:

1. An expansion end closure for tubes and the like comprising a cap formed with a central opening and an inwardly extending tubular lip around said opening, an annular series of spring prongs projecting from the inner face of the cap and having outwardly inclined ends for gripping at their edges the inner face of the tube, the prongs having a base portion formed with an opening for receiving said tubular lip, an expander in the form of a disk coating inclined plane fashion at its margin with the outwardly deflected ends of the prongs, and a screw extending through the cap and the tubular lip, and threading into the expander.

2. An expansion end closure for tubes and the like comprising a cap formed with a central opening and an annular lip projecting inwardly from the opening constituting a hollow rivet, spring prongs including portions lying flatwise against the inner face of the cap and mounted on the hollow rivet and secured to the cap there-

by, the prongs having outwardly inclined end portions for gripping the inner face of the tube, an expander disk coacting with its margin and said outwardly deflected end portions of the prongs,
5 and a screw extending through the opening in the cap and the hollow rivet and threading into the disk.

3. An expansion end closure for tubes and the like comprising a cap having a central opening and a tubular lip extending into the cap forming a hollow rivet, an annular series of spring prongs including a base portion common to the prongs

and lying flatwise against the inner face of the cap, the base being provided with a central opening mounted on the hollow rivet and secured to the cap by said hollow rivet, the prongs being formed with outwardly inclined ends for gripping the inner face of the tube, an expander disk coacting at its margin with said inclined ends of the prongs, a screw slidable through the opening in the cap and the hollow rivet and threading into the disk and having its head in said opening. 10

JOHN F. LEVAN.
